(57) **CLAIM**

The ornamental design for a golf travel bag, substantially as shown and described.

DESCRIPTION

FIG. 1 is a front elevational view of the design, FIG. 2 is a first side elevational view, the opposite side view being a mirror image, FIG. 3 is a rear elevational view, FIG. 4 is a top view, FIG. 5 is a bottom view; and, FIG. 6 is an elevational view of the first side and back. The broken line showing of environment in the drawings is for illustrative purposes only and forms no part of the claimed design.
